KNITTING MACHINE ATTACHMENT

James A. Ruth, High Point, N. C.

Application May 15, 1944, Serial No. 535,631

9 Claims. (Cl. 66—157)

This invention relates to a combined stop motion and latch opener for circular knitting machines wherein a unitary fitting is mounted on the latch ring and carries a detector for needles having broken butts or which may not for any reason have been lowered at the knitting wave and also carries a member adapted to engage latches of the needles of a knitting machine which may not have been opened properly upon being raised after passing the knitting wave, and also carries a latch opener adapted to be automatically thrown into operation for opening the needle latches during the knitting of the make-up portion of a sock or stocking, the raised needle detector and the closed latch detector being inter-connected together whereby when the closed latch detector is actuated, it will actuate a suitable stop motion device to stop the machine, and also where the raised needle detector is actuated, it will also actuate this same stop motion device to stop the machine, together with means for automatically withdrawing the raised needle detector during reciprocatory knitting together with automatic means whereby when the latch opener is placed into operation, the closed latch detector will be automatically withdrawn from operation, all of the above mechanisms co-operating with a single stop motion or belt shifter to shift the belt from a tight pulley to a loose pulley on the knitting machine.

It is an object of this invention to provide a combined stop motion and latch opener adapted to be attached to and pivoted with the latch ring of a knitting machine, whereby when the latch ring is pivoted upwardly, this combined stop motion and latch opener will move upwardly with the latch ring and be entirely out of the way of the needles and other operating mechanism associated with the cylinder.

It is another object of this invention to provide a broken butt needle detector, a closed latch detector, a latch opener, all provided with a unitary mounting disposed on and attached to the latch ring, the broken butt detector and the closed latch detector cooperating with each other to shift the belt on the knitting machine to stop rotation of the cylinder and also having a latch opener adapted to be automatically placed into operation during make-up knitting and having means for automatically withdrawing the closed latch detector from operation.

Some of the objects of the invention having been stated, other objects will appear as the description proceeds, when taken in connection with the accompanying drawings, in which:

Figure 1 is a top plan view of a circular knitting machine showing my invention associated therewith;

Figure 2 is an end elevation looking from the left-hand end of Figure 1;

Figure 3 is a top plan view on an enlarged scale of the upper left-hand portion of Figure 1;

Figure 4 is a cross-sectional view taken along the line 4—4 in Figure 3;

Figure 5 is a cross-sectional view taken along the line 5—5 in Figure 3.

Referring more specifically to the drawings, the numeral 10 indicates the cylinder housing of a knitting machine, only a portion of the frame work of this knitting machine being shown, including legs 10a, pattern drum 11, having conventional cams 12 thereon, the pattern drum being mounted on a shaft 13 and having a circular plate portion 14 within which the cylinder 15 revolves. Fixed on plate 14 is an upstanding forked portion 16 having a latch ring 17 pivoted between the two forks of member 16 as at 18. This latch ring has an upstanding portion 19 beneath which is pivotally mounted a plurality of yarn feed fingers 20. The free end of the latch ring 17 is adapted to fit down onto a post 22 and latched by means of a latch spring 23 engaging a pin 24 extending from the latch ring. Immediately below the latch ring is a sinker ring 25 having a plurality of sinkers 26 thereon adapted to cooperate with the needles 27 mounted in cylinder 15 of the knitting machine. The pattern drum 11 has associated therewith a plurality of push bars 30 for manipulating the yarn feed fingers and for throwing the same into and out of operation. One of these push bars 30 is adapted to engage a projection 31 on pivoted lever 32 for moving the gap closer mechanism to closed position. The upper end of arm 32 has pivotally secured thereto a rod 33 whose other end is pivoted in the gap closer 34 mounted on the latch ring 17. One end of the rod or link 33, as above-stated, is pivotally mounted in the upper end of lever 32 and has secured thereto a tension spring 36 whose other end is secured to a spring perch 37 secured to the latch ring which tends to hold the parts in the position shown in the drawings to thus leave the throat plate gap in open position. The conventional knitting machine also has a slotted bar 40 in which the push rods 30 operate, and it has a top table portion 41 and tight pulleys 42 and 43 and loose pulley 44 all shown in dotted lines in Figure 1 as being mounted on a drive shaft 45 also shown in dotted lines in Figure 1. The machine also has a conventional forked member 46 mounted on slidable rods 47 and 48 for shifting the belt from one of the tight pulleys 42 or 43 to the loose pulley 44 for stopping the knitting machine. The machine also has a vertically disposed flanged portion having a hole 49 therein in which a stand for supporting packages of yarn is held, said stand being omitted in the drawings.

60 Fixedly secured to the left-hand side of the

latch ring 17 and near its pivot point 18 by any suitable means such as screws 50 is a plate 51 on which the detectors and latch opener are mounted. A member 52 is pivotally mounted approximately midway its ends on a screw 53 which is threadably mounted in plate 51. This member 52 has upturned ends 54 and 55 in which is slidably mounted a raised needle detector finger 56 whose pointed end is adapted to overlap the needle circle and to project into the conventional cut-away portion in the latch ring immediately above the knitting cam so that as the needles pass this point, they should be in lowered or knitting position. This detector finger 56 is normally pressed to the position shown in the drawings by means of a compression spring 57 disposed between the upstanding end 54 and a collar 58 adjustably secured on the detector finger 56 by means of a set screw 60 which is adapted normally to lie flush against the inside surface of the upstanding projection 55. Secured around set screw 60 is a wire 61 which slidably penetrates a plate 62 fixed on the pivoted lever 32, said wire 61 having a stop collar 63 adjustably secured thereon and adapted to be engaged by the plate 62 when the gap closer is moved to gap closing position to thus withdraw the detector finger 56 from across the needle path. Member 52 has integral therewith and extending at approximate right angles thereto an arm 64 which has fixedly secured thereto by means of a screw 65 a wire portion 66 of a Bowden wire 67, this Bowden wire being secured in a clip 68 secured on the upstanding portion 19 of the latch ring.

The Bowden wire then extends rearwardly around to the rear of the machine and over onto the table portion 41 where it is fixedly secured in a clip 70 fixed on the table 41 and has the slideable wire portion 66 therein secured to a bell crank 73 by means of a screw 71 adjustably mounted in a slot 72 in one end of the bell crank latch 73 pivoted as at 74 on an upstanding portion 75 of a member 76 fixed on the table 41 by any suitable means such as screws 77. This portion 75 has mounted therein a set screw 78 adapted to limit movement of the latch end 80 of the bell crank latch 73. The latch portion 80 is adapted to engage the horizontal upper end 81 of a vertically disposed rod or shaft 82 rotatably mounted in the member 76 near its upper ends in a transverse member 83 at its lower end. This transverse member 83 is fixedly secured to two of the legs 10a of the knitting machine by any suitable means such as screws 84. The transverse member 83 has an inwardly and laterally projecting leg 85 extending to the side of the machine on which the pulleys 42, 43, and 44 are mounted. The vertical portion of shaft 82 is rotatably mounted in the portions 76 and 83, and near its lower end has a collar 87 fixedly secured thereon, which has integral therewith an arm 88 which has pivoted at the free end thereof a link 89. The other end of link 89 is pivoted as at 90 to an offset lever 91 which is pivoted as at 92 to the outer free end of the member 85. The member 91 then projects upwardly and beneath the drive shaft 45 and has an upwardly projecting pin 93 thereon which projects between the rods 47 and 48 and the fork 46 for shifting the fork 46 to thereby shift the belt on the pulleys 42 or 43 onto the pulley 44. The rear end of the lever 91 has secured thereto a tension spring 94 whose other end is secured to the transverse member 83 adjacent the left-hand post 10a as shown in Figure 1. Pivotally

secured to the pivoted member 52 for the detector finger 56 as at 100 is a bar 101 which is slotted as at 102 and is adjustably secured to a link 103 by means of a bolt 104. The link 103 has a slot 105 therein loosely penetrated by a bolt 106 mounted in member 107. The member 107 is pivotally mounted as at 108 in plate 51. Slidably mounted in upturned ends 110 and 111 of member 107 is a closed latch detector 112. This detector 112 is normally urged towards the needle circle by means of a compression spring 113 surrounding the detector 112. This detector 112 has adjustably secured thereon a block 114 by a set screw 115 which also receives and confines a wire portion 116 of a Bowden wire 117, which wire 117 is confined in a screw post 118 on plate 51. Pivotal movement of member 107 is limited in a counter-clockwise manner in Figure 3 by means of an adjustable stop plate 119 mounted on plate 51 by any suitable means such as a screw 125. The Bowden wire 117 extends downwardly and is secured as at 120 in the lower end of an arm 121 fixed on the periphery of plate 14. The wire portion 116 of the Bowden wire 117 is secured as at 122 to a lever 123 which is pivotally mounted as at 124 on one end of the rack member 40. The other end of lever 123 has a cam surface 130 adapted to engage a cam 131 on the end of the pattern drum 11 for raising the left-hand end 30 of lever 123 for a very short interval for the first few revolutions of the needle cylinder while the make-up of a stocking is being knitted. Pivotally secured to the lever 123 is a link 135 which has a turnbuckle mechanism 136 intermediate its ends 35 for adjusting the overall length of the rod or link 135. The upper end of the link 135 is connected to one end of a bell crank lever 140 pivoted as at 141 and the upstanding leg of lever 140 lightly engages a latch opening finger 142 whose operation will be presently described. When the left-hand end of lever 123 is raised upwardly by cam 131 in Figure 2, the wire 116 will be pulled downwardly which will move the detector needle 112 away from the needle circle.

The latch opening finger 142 is adjustably secured in a block 145 pivoted on screw 146, the member 142 being adjusted by means of a set screw 147. A tension spring 150 secured to spring perches 151 and 152 normally tends to pull the block 145 against a set screw 154 which is adjustably mounted in a bracket 155. When the link 135 is moved upwardly by cam surface 130 riding over cam 131, the upper end of lever 140 will allow tension spring 150 to pull the block 145 against set screw 154 and allow the free pointed end of finger 142 to pass inwardly to where it will engage the closed latches of the needles and open the same, this happening during the first few courses of knitting a stocking, or what is called the make-up operation. As before described, when the lever 140 is moved at its upper end in a clockwise manner as shown in Figure 2, the wire 116 of Bowden wire arrangement 117 will withdraw the point of member 112 from the needle circle and the pointed end of finger 142 will be substituted.

Method of operation

With the parts approximately in the position shown in the drawings, it is seen that the only connections between the various detecting devices fixed to the latch ring are connected by Bowden wires, or the slideable connection between the latch opener 142 and the lever 140. When it is desired to raise the latch ring, it is seen that since all of this mechanism is mounted on plate 51 affixed to

the latch ring, that all of the various mechanism shown in Figure 3 raises upwardly with the latch ring and thus prevents no obstruction to any work which is desired to be done on the needles or the cylinder.

The detector 56 is normally projected across the needle circle and above the lowered needles which are lowered in the knitting wave. In case a needle has its butt broken or for any other reason is not lowered in the knitting wave, this needle will strike the pointed end of the detector 56, and will swing the mounting 52 on pivot 53 which will pull wire 61 and will trip the latch 80 and allow tension spring 94 to swing lever 91 on its pivot 92 to thus shift the belt to the idler pulley. This swinging movement of member 52, it might be mentioned, is controlled in both directions by means of an adjustable stop 160 mounted on plate 51 by means of a screw 161. The natural position of lever 123 disposed in close proximity to the pattern wheel 11 normally holds lever 140 in a position to hold the latch opener finger 142 out of contact with the latches of the needles.

The member 52 is connected by means of links 101 and 103 to the member 107, but since this is a 10 slideable connection, when the detector 56 is engaged by a raised needle, the position of detector 112 for closed latches is not disturbed on account of the fact that bolt 106 will slide in slot 105. Now in case reciprocatory knitting is to be engaged in, the gap closer 34 will be moved by swinging of the lever 32 in a clockwise manner in Figure 3, and this will cause the wire 61 and its stop 63 by means of plate 62 to pull the detector needle finger 56 from across the needle circle so that this feature will be inoperative during reciprocatory knitting.

Instead of having a second Bowden wire or other connections between the belt shifting mechanism and the detector finger 112, it is noted that with the parts in the position as shown in the drawings, that if the detector 112 should engage a closed latch in a needle, it will swing the finger 112 along with its supporting member 107 on its pivot 108, and since the bolt 106 is near the upper end of the slot 105 in Figure 3, the swinging of needle 112 and its supporting member 107 will push links 103 and 101 as a unit away from the observer in Figures 1 and 3, and this will swing member 52 on its pivot 53 which will pull the wire 66 and operate the belt shifting mechanism in the same manner as if it had been a detection of a raised needle.

Now in case of knitting during a make-up, or the first few courses in a stocking, when it is not desired to employ the closed latch detector 112, it is to be noted that when the cam surface 130 rides onto cam 131, Bowden wire 116 will pull the closed latch detector 112 away from the needle circle, and the link 135 will swing the lever 140 in a clockwise manner on its pivot 141 in Figure 2 which will release the pressure on the other end of latch opener 142, and will allow its tension spring 150 to move block 145 against the end of set screw 154 which will allow the pointed end of the latch opener 142 to swing into a position where its pointed end will pass below the hooks of the needles and behind the closed latches, and thus open the latches during the make-up knitting in 55 a sock or stocking.

In the drawings and specification, there has been set forth a preferred embodiment of the invention and although specific terms are employed, they are used in a generic and descriptive sense 60

only and not for purposes of limitation, the scope of the invention being defined in the claims.

I claim:

1. In a knitting machine having a latch ring pivoted for upward movement relative to the needles, and having a slidably mounted fork for shifting the belt from a tight pulley to a loose pulley of the knitting machine and having a pattern drum, a plate fixedly secured on the latch ring, a plurality of detecting devices adapted to engage portions of the needles mounted on said plate, means for engaging said fork to shift the belt from the tight pulley on the knitting machine to the loose pulley, means normally urging the fork engaging means to move the fork to position the belt on the loose pulley, means for latching the fork engaging means in a position to hold the belt on a tight pulley of the knitting machine, interconnected means between said plurality of detecting devices mounted on said plate and the latch for actuating the latch to release the forked engaging means when any irregularity is detected by the detecting devices in the needles.

2. In a knitting machine having a pattern drum and belt shifting means for stopping the machine, said knitting machine also having a pivoted latch ring, a plate mounted on said latch ring and projecting laterally therefrom, a spring-pressed detecting finger mounted on said plate, and adapted to normally occupy a position extending across the needle circle immediately above the knitting cam, said detector finger being swingable when it engages a raised needle, and stop motion means operable by swinging movement of the detector finger for shifting the belt from a tight pulley to the loose pulley on the knitting machine, a second detecting finger swingably mounted on said plate and having spring-pressed means for holding it in position where its inner end will engage closed latches of a needle as the cylinder rotates the needles past the end of the second detecting finger, and means connecting the second detecting finger with the first detecting finger, so that upon engagement of a closed latch by the second detecting finger, both the first and second detecting fingers will be swung on their pivots, and the stop motion means will be actuated.

3. In a knitting machine having a rotatable needle cylinder and pattern drum and belt shifting means for moving the driving belt from a tight pulley to a loose pulley on the knitting machine drive shaft, a plate mounted on the latch ring and extending laterally thereof, a raised needle detector finger slidably and rotatably mounted on said plate, and adapted to normally occupy a position extending across the needle circle and above the knitting cam so as to engage needles which are not lowered in the knitting wave, a connection between said detector finger and the belt shifting means for allowing movement of the belt shifting means when said detector finger is engaged by a raised needle and swung on its pivot, a second detector finger mounted on said plate and being spring-pressed to cause its inner end to normally engage closed latches in needles passing by said inner end of the second detector finger, interconnected means between the second and first detector fingers for swinging the first detector finger when the second detector finger engages a closed latch of a needle, to thereby actuate the stop motion means, a lever pivoted adjacent the pattern drum, said pattern drum having a cam thereon adapted to be engaged by one end of the lever, a latch opener pivotally mounted

on said plate and normally biased to move into engagement with the latches of needles passing by its inner end to open latches during reciprocating knitting, a connection between the lever adjacent the pattern drum for withdrawing the second detector finger from engagement with the latches of needles passing thereby, and for allowing the swingable latch opener to move to an operative position when said lever engages the cam on said pattern drum.

4. In a circular knitting machine having a rotary cylinder provided with a plurality of needles and having a pattern drum and a belt shifting mechanism, and also having a pivoted latch ring, a bracket secured on one side of the latch ring and extending laterally thereof, a pivotally and slidably mounted finger for detecting raised needles mounted on said bracket, a pivotally and slidably mounted second finger mounted in said bracket for detecting closed latches in the needles, interconnecting means between the two fingers, said fingers being adapted to be swung when they engage a raised needle at the knitting wave or a closed latch in a raised needle, and means operable by swinging movement of either of said detector fingers for permitting operation of the belt shifting mechanism to shift the belt from a tight pulley to a loose pulley on the knitting machine.

5. In a circular knitting machine having a rotary cylinder provided with a plurality of needles and having a pattern drum and a belt shifting mechanism, and also having a pivoted latch ring, a bracket secured on one side of the latch ring and extending laterally thereof, a pivotally and slidably mounted finger for detecting raised needles mounted on said bracket, a pivotally and slidably mounted second finger mounted on said bracket for detecting closed latches in the needles, interconnecting means between the two fingers, said fingers being adapted to be swung when they engage a raised needle at the knitting wave or a closed latch in a raised needle, and means operable by swinging movement of either of said detector fingers for permitting operation of the belt shifting mechanism to shift the belt from a tight pulley to a loose pulley on the knitting machine, a swingable finger mounted on said bracket and normally biased to swing below the hooks of the needles and above the pivot points of the latches for opening the latches during reciprocating knitting, means for withdrawing the raised needle detector finger from across the needle circle during reciprocating knitting and means controlled by the pattern drum for allowing the latch opening finger to move into a position to engage and open latches of needles during a make-up operation, and also for withdrawing the closed latch detector from operative position during the knitting of a make-up portion of a stocking.

6. In a knitting machine having a pattern drum, a rotary needle cylinder, equipped with needles, and having loose and tight pulleys and a belt shifter for shifting the belt from one pulley to another, a slidably and pivotally mounted detector finger normally biased to move across the needle circle to engage a raised needle as it passes the knitting cam, a second detector finger slidably and pivotally mounted and normally urged to move to a position to engage closed latches of needles as they pass the end of the second finger, means interconnecting the two fingers so that swinging movement of the second finger upon

engagement with a closed latch will also swing the first finger and actuate the means for permitting the shifting mechanism to shift the belt from a tight pulley to a loose pulley on a knitting machine.

5. In a knitting machine having a rotary needle cylinder equipped with needles and having a pivoted latch ring and a pattern drum and loose and tight pulleys and a belt shifting mechanism, a bracket mounted on the pivoted latch ring and extending laterally thereof, a detector finger slidably and pivotally mounted on the bracket, and extending across the needle circle above the knitting cam, a second finger slidably and pivotally mounted on the bracket and extending to a point to engage closed latches of needles passing by its end, means for holding the belt shifting mechanism in a position to hold a belt on a tight pulley of the machine and means controlled by the swinging of either of said detector fingers upon engagement with a needle for actuating the means for moving the belt shifting mechanism to shift the belt from a tight pulley to a loose pulley on the knitting machine.

8. In a knitting machine having a rotary needle cylinder equipped with needles and having a pivoted latch ring and a pattern drum and loose and tight pulleys and a belt shifting mechanism, a bracket mounted on the pivoted latch ring and extending laterally thereof, a detector finger slidably and pivotally mounted on the bracket, and extending across the needle circle above the knitting cam, a second finger slidably and pivotally mounted on the bracket and extending to a point to engage closed latches of needles passing by its end, means for holding the belt shifting mechanism in a position to hold a belt on a tight pulley of the machine and means controlled by the swinging of either of said detector fingers upon engagement with a needle for actuating the means for moving the belt shifting mechanism to shift the belt from a tight pulley to a loose pulley on the knitting machine, a swingable latch opener mounted on the plate, means controlled by the pattern drum for allowing movement of the latch opener to engage and open latches during knitting of a make-up portion of a stocking and said pattern drum controlled means also withdrawing the closed latch detector from operative engagement with the latches of needles.

9. In a knitting machine having a latch ring pivoted for upward movement relative to the needles and having a slidably mounted fork for shifting the belt from a tight pulley to a loose pulley of the knitting machine, and also having a gap closer for closing the throat of the latch ring during reciprocating knitting, together with means for moving the gap closer across the throat of the latch ring, a plate mounted on the latch ring, a detector finger swingably mounted on said plate and biased to project across the needle circle immediately above the knitting cam employed during rotary knitting, means for normally holding the belt shifting means in position to hold the belt on a tight pulley, means controlled by swinging of the detector finger by engagement with a raised needle for allowing the belt shifting means to shift the belt from a tight pulley to a loose pulley, and means operable by the moving of the gap closed to closed position for withdrawing said detector finger from across the needle circle.
